Primary Examiner — Jennifer Rivard(74) *Attorney, Agent, or Firm* — Lee & Hayes, PLLC(57) **CLAIM**

The ornamental design for a hinged cosmetic receptacle, as shown and described.

DESCRIPTION

FIG. 1 is a perspective view of a hinged cosmetic receptacle; FIG. 2 is a front elevation view of the hinged cosmetic receptacle of FIG. 1;

FIG. 3 is a back elevation view of the hinged cosmetic receptacle of FIG. 1;

FIG. 4 is a left-side elevation view of the hinged cosmetic receptacle of FIG. 1, the right-side elevation view being a mirror image of the left-side elevation view;

FIG. 5 is a top plan view of the hinged cosmetic receptacle of FIG. 1; and,

FIG. 6 is a bottom plan view of the hinged cosmetic receptacle of FIG. 1.
